UNITED STATES PATENT OFFICE

102,387

DESIGN FOR A BEAM COMPASS OR THE LIKE

Wade Moses, Cleveland, Ohio

Application May 1, 1936, Serial No. 62,400

Term of patent 14 years

To all whom it may concern:

Be it known that I, Wade Moses, a citizen of the United States, residing at Cleveland, in the county of Cuyahoga and State of Ohio, have invented a new, original, and ornamental Design for a Beam Compass or the Like, of which the following is a specification, reference being had to the accompanying drawing, forming part thereof, wherein Figure 1 is a plan view; Fig-

ure 2 is a side elevation; Figure 3 is a sectional view looking in the direction of arrow "A"; Figure 4 is a sectional view looking in the direction of arrow "B", and Figure 5 is a sectional view looking in the direction of arrow "C".

I claim:

The ornamental design for a beam compass or the like, as shown.

WADE MOSES.
